Charles Le Bleu, Los Angeles, Calif.

Application July 29, 1935, Serial No. 33,633

3 Claims. (Cl. 37—129)

This invention relates to material moving devices adapted to be moved across a surface to be treated, by a vehicle such as a tractor, for the purpose of scraping up and removing materials. 5 More specifically the invention relates to that class of material moving devices having a revolute bucket designed and adapted to assume excavating, carrying and dumping positions, and an auxiliary dirt retaining member disposed forwardly of said revolute bucket. In my Patent 10 No. 1,891,427 dated December 20, 1932, I disclose such a device, in which the auxiliary dirt retaining member is represented by reference number 44. It will be noted by reference to Figures 1 15 and 2 of Patent No. 1,891,427 that the apron 44 comprises side walls and an inclined forward wall which has no bottom portion that will serve as an earth supporting bottom member. Furthermore, as shown in Figure 4 of Patent No. 20 1,891,427, which is the loading position, the apron is automatically raised and tilted by operation of the control mechanism to cause the bucket B to assume the position shown and apron 44 will not serve as a material supporting bottom 25 member in this position, and it is therefore an object of the invention disclosed in this present application to so construct, arrange and control the auxiliary dirt retaining member that it will serve as an auxiliary bucket to be loaded in conjunction with the revolute bucket to the end 30 that a larger load may be obtained with a given amount of power.

Another object of the invention is the provision in a material moving device having a 35 revolute bucket and an auxiliary bucket disposed forwardly of the revolving bucket whereby when the revolving bucket becomes loaded materials will move into the auxiliary bucket.

Another object is the provision in a scraper 40 having a revolute bucket and an auxiliary bucket disposed forwardly thereof, of independently operable control mechanism for each of said buckets.

Another object is the provision in a material 45 moving device of a material carrier comprising, a revolute bucket provided with a material scraping and receiving edge, and an auxiliary bucket disposed forwardly of said revolute bucket and arranged relative thereto to be loaded in conjunction therewith.

Another object is the provision in a material 50 moving device of a revolute bucket, and means whereby said bucket may be revolved backwardly to dump the load.

55 Another object is the provision in a material

moving device of a draft frame, a revolute bucket having a material scraping and receiving edge, an auxiliary bucket disposed forwardly of said revolving bucket arranged relative thereto to be loaded in conjunction therewith and means 5 mounting said revolute bucket, said auxiliary bucket and said frame about a common axis.

Another object is the provision in a material moving device of a frame, a main bucket mounted thereon, an auxiliary bucket disposed forwardly of said main bucket and arranged relative thereto, and means continuously acting upon said auxiliary bucket to minimize the tendency to downward movement because of its 10 weight. 15

Another object is the provision in a material moving device including a main frame; a revolute bucket and auxiliary bucket; of means whereby the materials in both of said buckets may be dumped rearwardly of the scraper. 20

Another object is the provision in a material moving device including a revolute bucket and an auxiliary bucket disposed forwardly thereof and arranged relative thereto to be loaded in conjunction therewith, of power operated control 25 means to rotate said revolute bucket, hold said bucket stationary in a selected position, or release said bucket for revolving movement.

These and other objects are attained by the embodiment of my invention illustrated in the 30 accompanying drawings which:

Figure 1 is a side elevation of the preferred form of the device in load carrying position showing latch mechanism for latching the two buckets together for rear dumping. 35

Figure 2 is a fragmentary plan view of the device as shown in Fig. 1 showing a plan view of said latch mechanism.

Figure 3 is an enlarged plan view of the rear dumping latch member. 40

Figure 4 is an enlarged side view of the rear dump latch member.

Figure 5 is a side elevation in section of the revolute bucket shown in Figures 1 and 6. 45

Figure 6 is a side elevation of the device in the act of tilting rearwardly.

Figure 7 is a side elevation showing how the materials from both buckets are dumped rearwardly.

Figure 8 is a side elevation showing the revolute bucket in upside down position and the auxiliary bucket in normal position. 50

Referring now more particularly to the characters of reference on the drawings, F is a frame comprising side arms 3, 3 connected at their for- 55

ward ends to the outer ends of a cross beam. Connected to the cross beam and extending forwardly therefrom is a draft beam 1 adapted at its forward end for connection to a draft device, 5 such as a tractor. Extending between the rear ends of side arms 3, 3 and journaled thereon is a revoluble bucket 4 provided at its opposite ends with two hoods 5, 5 forming a part of the revoluble bucket and open on their under sides 10 within these hoods are rolling supports 33 mounted upon bearings supported in the ends of the revoluble bucket as at 6, 6, and in the inner sides of the hoods 5, 5. The forward side of the bucket at opposite ends thereof is provided with 15 the usual runners or shoes 8, 8. Secured at the forward lower edge of the bucket is a material scraping and receiving edge 9. The forward walls 12, 12 of the hoods may be formed whereby the scraping edge 9 extends only between the 20 inner walls of the hoods and short scraping edges 11, 11 are attached to the lower portion of the forward walls 12, 12 of the hoods. When the forward walls, 12 of the hoods are formed as in Figure 5 the scraping edge 9 extends the entire 25 distance between the bucket head plates 13, 13. Secured to each of the bucket head plates 13, 13 is a pair of stops 14, 14 and 15, 15 comprising outwardly projecting pins carrying rollers.

Disposed forwardly of the revoluble bucket 30 and arranged relative thereto is an auxiliary bucket 16 open at its rear side and having rearwardly extending arms 17, 17 journaled at their rear ends on said revoluble bucket in common with the frame F. Mounted on the rearwardly 35 extending arms 17 at 19 is a latch member 18 adapted to engage the stops 15 on the head plates 13, and having an upwardly extending arm 20 provided at its upper end with a pull rope 21 extending forwardly to within easy reach of 40 the operator of the tractor for manual operation.

Extending transversely of the frame F and suitably journaled thereon in bearings such as at 22, 23, and 24, is crank shaft 25 provided at each end thereof with crank arms 26, 26. Pivotally secured at the outer ends of crank arms 26 45 by pins 27 is the forward ends of control bars 28 pivotally connected forwardly of their rear ends by a pin 29 to the lower end of links 30, 30 pivotally connected at their upper ends by means 50 of pins 31, 31, to side arms 3, 3 of the frame F. The rearwardly projecting ends 32 of control bars 28 are arranged and adapted to engage or disengage stops 14, 14 and 15, 15 on the head plates of the revoluble bucket 4.

55 The lower portion of the forward wall of the auxiliary bucket 16 is provided with a bracket 34. Secured to bracket 34 at 35 is a cable 36. Mounted on the frame F is bracket 37 carrying sheave 38. Cable 36 extends upwardly thence 60 over sheave 38 and forwardly under a direction change sheave 39, thence to a winding drum unit on the tractor (not shown because conventional).

Secured to crank shaft 25 is a crank arm 40 carrying at its upper end a sheave 41. Secured 65 to frame F is direction change sheave 42. Secured to frame F at 43 is a cable 44. Cable 44 passes upwardly and over sheave 41, thence under direction change sheave 42, thence forwardly to a winding drum unit on the tractor (not 70 shown because conventional).

While no specific showing is made of a control mechanism operated by cables and a winding drum, still it will be apparent to one versed in the art that other means, such as a hydraulic ram 75 mechanism, as indicated in my U. S. Letters Pat-

ent No. 1,958,195 may be substituted for the winding drum to draw the cables without departing from the spirit of the invention.

In operation the device is attached at 57 to a suitable draft device, such as a tractor, to be 5 advanced across a surface to be treated thereby. The revoluble bucket 4 is pivotally connected to the frame at 6 rearwardly of the center of gravity of said bucket so that said bucket normally tends to revolve clockwise. The winding drum (not shown) carrying cable 44 is released thus allowing revoluble bucket 4 to rotate forwardly or clockwise causing link 30 and crank arm 26 to swing downwardly and forwardly. When the bucket 4 has assumed a scraping position, it will 10 be adjustably retained in position by control bars 28 engaging stops 14. As the device advances while in this position materials will be scraped up by the material scraping and receiving edge. When both buckets are loaded the 15 winding drum (not shown) is operated to rewind cable 44 resulting in swinging crank arm 40 forwardly thus rotating crank shaft 25 and swing links 30 and crank arms 26 rearwardly and upwardly thus raising control bars 28 and reversely 20 rotating bucket 4 to the carrying position. In this position the materials may be transported to any desired location. Now the buckets may be unloaded by revolving bucket 4 either forwardly or backwardly. To unload while moving 25 forwardly, the winding drum (not shown) carrying cable 44 is released allowing the control bars 28 till such time as stops 14 have passed the rear ends of control bars 28, at which time the winding drum (not shown) carrying cable 30 35 44 is operated to rewind cable 44 and again position the rear end of control bars 28 in the path of the stops on the bucket head plates. Bucket 4 will continue to rotate forwardly while advancing until stops 15 engage control bars 28. 40 Thus the device is caused to assume a dumping position while moving forwardly and continued forward movement of the device will result in spilling the load. When the load has been discharged, cable 44 is again operated to manipulate 45 control bars 28 and release stops 15, and engage the stops 14. Discharging the materials rearwardly that is, by reversely rotating bucket 4, is usually desired only when the materials are to be dumped into a depression into which it is 50 impractical to drive the tractor and the device. In such cases rear dumping is accomplished as follows: The device is backed up to a point near the rim of the depression. Then pull rope 21 is manipulated to cause latch member 18 to engage 55 stops 15. While holding latch member 18 into engagement with stops 15 as shown in Figure 6, a winding drum (not shown) carrying cable 36 is operated to wind cable 36 and thus tilt the buckets into positions shown in Figures 60 6 and 7. At this point the lower rear side of bucket 4 will have contacted the ground and the materials in the auxiliary bucket 16 will have spilled rearwardly as shown in Figure 7. Then 65 complete dumping of bucket 4 is accomplished by backing up the device resulting in reverse rotation thereof to the position shown in Figure 8. Then when a tractor or other draft vehicle not shown in the drawings is reversed and again moved forward the bucket 4 will rotate clockwise leaving the materials deposited in the depression, bucket 16 having previously been returned from the position shown in Figure 7 to that of Figure 8. Then the forward movement 70 75

is continued till stops 14 again engage control bars 28.

From the foregoing description it will be apparent to one versed in the art that I have disclosed a device as substantially fulfills the objects of the invention as set forth, and while this specification sets forth in detail the present and preferred construction of the device, in practice such arrangement, correlation and construction 10 of parts, members and features may be resorted to as do not form a departure from the spirit of the invention, as defined in the appended claims.

Having thus described my invention, what I claim as new and useful and desire to secure by 15 Letters Patent is:

1. A device of the class described comprising, a frame adapted to be moved across the surface of the earth, a bucket, an auxiliary bucket disposed forwardly of said first mentioned bucket 20 and arranged relative thereto to be loaded in conjunction therewith, means operably associating said buckets and said frame about a common axis, means pivotally mounting said auxiliary bucket on the pivotal connection of said revolvable bucket with said frame and means operable by 25 to cause said device to assume operative and inoperative positions.

2. A device of the class described comprising,

a frame adapted to be moved across the surface of the earth, a bucket provided with a material scraping and receiving edge for scraping up and loading materials, means pivotally connecting said frame and said bucket, an auxiliary 5 bucket disposed forwardly of said first named bucket and arranged relative thereto to be loaded in conjunction therewith, means pivotally mounting said auxiliary bucket on the pivotal connection of said revolvable bucket with said frame, and means to cause the device to assume operative and inoperative positions.

3. In a scraper a main bucket comprising a bottom and backwall and side walls therefor, a scraper disposed at the forward end of said bottom for scraping up material, an auxiliary bucket including a bottom and side walls therefor disposed in front of said main bucket and confronting the same to be loaded in common therewith, means pivotally mounting said auxiliary bucket 15 on the pivotal connection of said main bucket for vertical swinging movement, the contiguous side walls of both buckets being substantially in a common plane and formed with their adjacent edges concentric with the pivotal mounting of 20 said auxiliary bucket.

CHARLES LE BLEU.
